ATTEST,

James Thierry
H. F. Ebert,

INVENTOR,

George R. Chandler
Per Attorney
Thos. Sprague

United States Patent Office.

GEORGE R. CHANDLER, OF DETROIT, MICHIGAN.

Letters Patent No. 101,226, dated March 29, 1870.

IMPROVED WASHING-MACHINE.

The Schedule referred to in these Letters Patent and making part of the same.

To whom it may concern:

Be it known that I, GEORGE R. CHANDLER, of Detroit, in the county of Wayne and State of Michigan, have invented a new and useful Improvement in Washing-Machines; and I do declare that the following is a true and accurate description thereof, reference being had to the accompanying drawings and to the letters of reference marked thereon, and being a part of this specification, in which—

Figure 1 is an elevation, partially in section, of my device attached to a wash-tub; and

Figure 2 is a cross-section of the rolls.

Like letters indicate like parts in each figure.

The nature of this invention relates to an improvement in washing-machines, and consists in the construction and arrangement of a pair of corrugated wooden rollers in a suitable frame, and in the method of attaching the device to a wash-tub, in which the process of cleansing the clothes may be performed in the manner hereinafter set forth.

In the drawings—

A are a pair of short standards, connected by a cross-piece, B, at their upper ends. The cross-piece is of sufficient length to reach across an ordinary wash-tub, C.

D is a corrugated roller of wood, journaled in the standards and rotated by a crank, E.

D' is a similar roller, but hung by its spindles in the eyes formed in the lower ends of the rods F which pass down through or nearly through the standards.

The opening in the standards is counter-bored in

the upper half for the reception of a spring, G, coiled about the rod, pressing up against a wooden washer, H, between it and the adjusting-screw I.

J are clamps, pivoted to either end of the cross-bar, and clamp the walls of the tub, between their lower ends and those of the standards, by means of the clamp-screws K.

The operation of the device is as follows:

The soiled fabrics are immersed in hot suds in the tub; the operator gives the rolls an alternating circular motion with one hand by means of the crank; with the other hand a garment is introduced between the rolls, and moved back and forth between them; the desired pressure is given by the adjusting-screws, and, when cleansed, it is discharged over the side of the tub into another containing clean water, for rinsing, the garment being partially dried in its last passage through the rolls.

I expressly disclaim the invention of rolls for wringing clothes that have been cleansed; but

What I do claim as my invention, and desire to secure by Letters Patent, is—

The construction and arrangement of the standards A, cross-bar B, clamps J, screws K, rods F, nuts I, washers H, springs G, rolls D D', and crank E, in the manner and for the purpose set forth.

GEO. R. CHANDLER.
